UNITED STATES PATENT OFFICE.

HEINRICH BOCKISCH, OF POUGHKEEPSIE, NEW YORK, ASSIGNEE, BY MESNE ASSIGNMENTS, TO WELTE-MIGNON CORPORATION, OF NEW YORK, N. Y., A CORPORATION OF NEW YORK.

AUTOMATIC MUSICAL INSTRUMENT.

Application filed December 12, 1918. Serial No. 344,316.

To all whom it may concern:

Be it known that I, HEINRICH BOCKISCH, a citizen of Czechoslovakia, residing at Poughkeepsie, in the county of Dutchess and State of New York, have invented certain new and useful Improvements in Automatic Musical Instruments, of which the following is a specification.

This invention is a particular embodiment 10 of a mechanism wherein there is a plurality of series, or scales, of tone-emitting elements, as organ pipes, for example, one of said series being for tones having a different quality than the other, as pedal and 15 manual, for instance, together with record-controlled means for selectively causing the operation of any one or more of the tone-emitting elements of either series alone, or of any one or more of the elements of one series 20 in combination with any one or more of the elements of the other series.

The embodiment illustrated in the accompanying drawings comprises many parts and correlations of parts which are generally similar to what has been shown, described and claimed in my patents numbered 1,197,573; 1,197,574; and 1,197,575 issued September 5, 1916, and also in my applications for patents numbered serially 30 339260 and 339261 respectively, filed November 20, 1919.

There is a particularly close relationship between the embodiment herein illustrated by way of example in my aforesaid applications for letters patent identified as "Case A" and "Case B" respectively, the substantial differences being in those parts of the switching mechanism for the pedal and manual scales entitled "primary operating 40 pneumatic elements," together with the connections between the same and the circuit closing elements, the tone circuits, and also in the details of the pneumatically operated locking mechanism.

The drawing of "Case A" hereinbefore referred to illustrates an embodiment of my invention wherein there are two series of separate bellows, one for the pedal scale and

the other for the manual scale, each bellows having its movable board pivoted with a circuit closing member, and two series of separate bellows, one series for the pedal scale and the other series for the manual scale, each bellows having a projection movable into the path of the corresponding circuit closing member to thereby hold said member against movement from the position to which it was set until the corresponding tone duct has been closed, even though a control duct meanwhile be opened or closed.

The drawing of "Case B" hereinbefore referred to illustrates an embodiment of my invention wherein there are two series of separate circuit closing devices, such as levers carrying the circuit closing members, one series for the pedal scale, and the other series for the manual scale, together with operating pneumatics respectively common to the series of levers, and connections between the pneumatics and the series of levers, the connections including an operating member common to each series of levers and resiliently supported stems connecting each lever with its common operating member.

In the present invention I have provided in lieu of the particular embodiments referred to in "Case A" and "Case B" respectively, a series of circuit closing devices, such as levers for each scale, each lever having a circuit closing member, and a membranous means for each series of levers, the membranous means being connected to the respective levers by stems which engage said means and levers; and in lieu of the locking bellows and their projections illustrated in the drawings of each of the foregoing applications, the present embodiment employs a series of locking levers and membranous means and stems similar to the membranous means and stems employed to operate the levers which carry the circuit closing member, each of said locking levers having a projection to act as a stop for the corresponding circuit closing lever. Further distinctions between the present em-

bodiment and the embodiments illustrated by the drawings of the foregoing applications for patents are as follows:

In the embodiment set forth in this application the stems which operate the respective circuit closing levers are in position to be moved by the membranous means but are disconnected so that each may be capable of independent movement relative to the other. Also the stems are operated upon directly by the membranous means, and in turn directly operate the levers. Moreover, these stems of the circuit closing and locking levers are movable in a straight line and are loosely connected to the levers.

In the drawings illustrating a preferred embodiment of the invention, and wherein like characters of reference denote corresponding parts in the several figures:

Figure 1 is a diagrammatic view of a complete mechanism including the improvements which constitute the present invention.

Fig. 2 is a perspective view, partly in section, of a part of the switching mechanism of the manual scale, together with locking valves which control the air tensions in the channels adjacent the membranes, which operate the locking elements and with electromagnets for controlling the air tensions to the membranes for operating the locking valves.

Fig. 3 is a vertical section through the switching mechanism showing corresponding switching elements of the manual and pedal scales and their cooperating locking elements, together with the common control valve for the locking elements and the magnet for controlling the valve, the parts being shown in their relation when the corresponding tone duct was opened before either control duct and which relation is maintained until said tone duct is closed.

Fig. 4 is a section on line 4-4 of Fig. 3.

Fig. 5 is a section on line 5-5 of Fig. 3.

Referring to Fig. 1 of the drawings:

D is a tracker board having the mouths of tone ducts 12 common to a plurality of scales, as a manual scale and pedal scale, for example, and also having the mouths of control ducts 1 and 2.

14 designates a primary tone valve whose stem is connected to a membrane 17 mounted between a chamber 13 and a suction conduit 13^a, the valve itself being mounted in a chamber 14^a, having a suction port 20 and an atmospheric port 19. In practice there is one of these valves, membranes, chamber 13, and chamber 14^a for each note common to both scales, and additional valves, membranes and chambers for each note which is to be played in the manual scale only, for example. As this invention is concerned only with those notes which are common to a plurality of scales, the description will

be confined to the parts by which the sounding of the notes in either scale alone, or in both scales together, in any combination called for by the musical composition, is permitted, notwithstanding the use of primary tone valves and tone ducts common to both scales. It will be understood that the several chambers 13 and 14^a are, in practice preferably embodied in a chest (a section of which is shown at K) called primary 75 tone chest, and that the conduit 13^a, also in said chest, may be common to the several valves 14 and membranes 17 and suitably connected with a means for attenuating the air therein. The ducts 12 are connected to 80 the chambers 13, respectively, and serve to admit atmospheric air to the membranes 17 to thereby move the primary tone valves 14 to close the atmospheric ducts 19 and open the suction ducts 20. Each section of the 85 chest K also has a pneumatic g^a provided with primary circuit closers g^a, respectively, for closing tone circuits hereinafter fully set forth.

F and H designate secondary operating 90 pneumatics, having suitable connections, such as indicated at F' and H', for example, with the stems e^a of valves (not shown) in the manual and pedal wind chests as in my patents and applications for patent herein- 95 before referred to. In practice, there is one pneumatic F for each valve in the manual wind chest section and one pneumatic H for each valve in the pedal wind chest section.

Each pneumatic F is connected to a chamber 63. The several chambers 63 provided, in practice, are preferably formed in a secondary tone chest, a section of which is shown at I. Similarly, each pneumatic H is connected to a chamber 63 and these several chambers 63 are preferably formed in a secondary tone chest, a section of which is shown at I'.

Each chamber 63 is provided with a secondary tone valve 70, and is formed with a 110 suction port 64 and an atmospheric port 65. The valves 70 are severally moved to close the respective atmospheric ports 65 and open the respective suction ports 64 and thereby collapse the corresponding pneumatic F or 115 H by admitting air at atmospheric pressure to chambers 66 having membranes 67 connected to the valves 70. This air is admitted to said chambers 66 through ducts 69, and these ducts are opened and closed by valves 120 68 carried by the armatures f, h, of electromagnets f and h which are included in the tone circuits hereinafter fully set forth.

The control ducts 1 and 2 hereinbefore referred to respectively lead to chambers 3 and 125 3^a, formed in primary control members J and J'. The member J also has a suction chamber 4, a valve chamber 5, a suction port 6, an atmospheric port 7, a valve 8 in the chamber 5 to control said ports, a mem- 130

brane 9, mounted between the chambers 3 and 4 and connected to the stem of the valve 8, and a pneumatic a^6 having connection with the valve chamber 5, through a port 10, and provided with a circuit closing member b^5 . The member J' does or may embody the same construction as member J ; 3 a being the chamber connected to the duct 2; 4 a being its suction chamber; 5 a its valve chamber; 6 a and 7 a its suction and atmospheric ports, respectively; 8 a its valve; 9 a its membrane; and a^6 its pneumatic, having connection with chamber 5 a through port 10 a and provided with a circuit closing member a^5 .

The circuit closing member b^5 closes a "pedal control circuit," hereinafter described, the effect of which is to complete otherwise interrupted tone circuits which control the playing of pedal notes, whereby pedal notes are sounded when duct 1 is opened. The circuit closing member a^5 closes a "manual control circuit" hereinafter described, which results, as hereinafter explained, in the interruption of the tone circuits to the manual scale, when control duct 2 is opened, to thereby exclude manual notes and, hence, duct 2 is opened along with control duct 1 to cause the sounding of notes in the pedal scale only.

E designates a primary operating pneumatic element of a membranous nature for the manual scale and G a primary operating pneumatic element of a membranous nature for the pedal scale. In this particular embodiment of the invention the element E is a long membrane for the entire scale, having one of its surfaces exposed to the air in a channel O. This air is normally at atmospheric pressure, and means are provided for changing its tension to less than atmospheric under control of the primary control member J' , through an intermediate mechanism which preferably includes a secondary control valve having a stem 25 and valve members or heads 26 and 27. These valve members in this particular embodiment are mounted in a chamber 28 having a suction port 29, an atmospheric port 30 and a duct 24. The duct 24 connects the chamber 28 and the channel O. The stem 25 engages a membrane 31 which separates a suction chamber 32 from a chamber 33. The latter chamber is connected by a duct 34 with a passage 35, one end of which is open to the atmosphere and the other end of which extends to a suction chamber 36. A valve, comprising a stem 37 which extends through the passage 35, and valve members or heads 38 and 39, controls the passage 35 to open communication of duct 34 with the atmosphere or with the suction chamber 36 and this valve is operated, to change the tension of the air in said duct and hence in chamber 33, by a membrane 40 which is arranged

between the suction chamber 36 and a chamber 41 having a duct 42 which is opened and closed by a valve 43 carried by the armature 44 of an electro-magnet 45. This magnet is in the manual control circuit, 70 which is opened and closed by the circuit closing member a^5 and hence the magnet is controlled by control duct 2 through the primary control member J' .

The parts are so correlated that when the 75 duct 2 is closed, the circuit to the magnet 45 is broken; duct 42 will be closed, chamber 41 will be under suction through a bleed hole 46 connecting chamber 36 with chamber 41, passage 35 will be in communication 80 with suction chamber 36 and closed to the atmosphere, chamber 33 will be under suction through duct 34, chamber 28 will be in communication with the atmosphere, and accordingly, channel O will contain air at atmospheric pressure supplied thereto through duct 24, chamber 28 and atmospheric port 30.

G designates a primary operating pneumatic element for the pedal scale. This element, also, is of a membranous nature and 90 preferably is formed of a long membrane common to the entire scale. One of its surfaces is exposed to a channel N which contains air at normally less than atmospheric pressure, and means are provided for changing its tension to atmospheric pressure under control of the primary control member J . This means may be substantially similar to that already described with relation to the channel O, and is so shown; 50 being the 100 duct which extends to the channel N and is in communication alternately with a suction chamber 32 a and with the atmosphere under control of a valve which comprises a stem 25 a arranged in a channel 28 a and provided 105 with valve members or heads 29 a and 30 a ; 31 a being a membrane for operating the valve, arranged between the suction chamber 32 a and a chamber 33 a , the latter having a duct 34 a which extends to another passage 110 35 a , in which is mounted the stem 37 a of a valve having heads or valve members 38 a and 39 a , the last named valve being operated by a membrane 40 a arranged between a suction chamber 36 a and a separate chamber 41 a , the latter having a duct 42 a whose mouth is opened and closed by a valve 43 a carried by the armature 44 a of an electro-magnet 45 a which is in the pedal control circuit, hereinafter described, opened and 115 closed by the circuit closing member b^5 under control of control duct 1 through the primary control member J .

The parts are so correlated that when the duct 1 is closed, the circuit to magnet 45 a 125 will be broken, duct 42 a will be closed against the atmosphere, chamber 41 a will be under suction, through a bleed hole 46 a , passage 35 a will be open to the suction chamber 36 a and closed to the atmosphere, the 130

air in duct 34^a and chamber 33^a will be attenuated, passage 28^a will be open to suction chamber 32^a and closed to the atmosphere, and, in consequence, the air in duct 50 and channel N will be attenuated.

58 and 61 designate circuit closing devices, such as levers carrying secondary tone-circuit closing elements g and e. These levers are pivoted at 58^a and 61^a respectively and 10 are provided with means, as springs 59 and 62, to exert thereon resilient pressure in a direction toward the membranes G and E, with which membranes the levers are connected by stems 51 and 51^a having heads 52 15 and 52^a to engage the levers. It will also be understood that the purpose of the springs 59 and 62 is to press the levers 58 and 61 to force the contacts g away from wires c, c', and contacts e away from 20 wires d, d'. The stems 51 and 51^a are loosely engaged with their respective levers 58 and 61.

75 and 77 designate pneumatically operable locking or holding levers having projections 76^a and 78^a which are movable into the paths of projections 76 and 78 of the respective levers 58 and 61. These levers 75 and 77 are respectively pivoted at 75^a and 77^a and they are connected with membranes 79 and 80 by rods or stems 79^a and 80^a which are loosely engaged with the respective levers and have heads 79^b and 80^b to contact the latter. The levers also have means, as springs 79^c and 80^c, acting in 35 opposition to the air tension exerted on the levers through the membranes 79 and 80 and stems 79^a and 80^a.

The loose connection of each stem 51, 51^a, 79^a and 80^a with their respective levers, is 40 preferably effected by forming the levers with openings and extending the ends of the levers into said openings. The purpose of the loose connection is to permit relative movement of the levers and stems.

45 81 designates a channel from which extends a duct 81^a having branches 81^b and 81^c. The branch 81^b communicates with a chamber 79^d beneath the membrane 79 and the branch 81^c with a like chamber 80^d beneath the membrane 80.

It will be noted that the channel 81 has 50 communication with the chambers 80^d and 79^d and, accordingly, that if the air in channel 81 be rarefied or if it be at atmospheric pressure, it will similarly be rarefied or at 55 atmospheric pressure, as the case may be, in both chambers 79^d and 80^d. The channel 81 is controlled, to thereby control the tension of the air in chambers 79^d and 80^d, preferably by a valve which comprises a stem 86 having heads or valve members 84 and 85. In this exemplification, the stem 86 extends 60 through a port or channel 82, one end of which communicates with a suction chamber 83 and the other end of which is open

to the atmosphere. This valve is operated by a membrane 88, one surface of which is exposed to the rarefied air in the chamber 83 and the other surface of which is exposed to the air in a chamber 87 having a 70 duct 90, the mouth of which is opened and closed by a valve 92 carried by the armature 91^a of an electro-magnet 91. A bleed hole 89 connects the chambers 83 and 87 with each other. The magnet 91 is energized 75 when the corresponding primary tone-valve 14 is opened, being in a circuit hereinafter described which is controlled by said valve, and accordingly is primarily controlled by the corresponding tone duct 12. In other 80 words, the magnets 91 are in tone circuits.

In practice there is one circuit closing device as the lever 61 for each note of the manual scale which has a corresponding note in the pedal scale, and one holding lever 85 77 for each lever 61 and the series of levers 61 and 77 are preferably mounted in a chamber which is under suction from a suitable source. Similarly, there is one circuit closing device as the lever 58 for each note of 90 the pedal scale which has a corresponding note in the manual scale, and one holding lever 75 for each lever 58, and the series of levers 58 and 75 are preferably in a chamber which is under suction. In the diagrammatic view (Fig. 1) the tension chambers are separately designated, being marked M' and L' respectively and shown as being in suitable boxes or chests M and L. There is also one magnet 91 for each note which 100 is to be played in either the manual scale or the pedal scale, one locking valve having valve members 84 and 85 for each magnet 91 and each pair of locking or holding levers 75 and 77. 105

The chamber M' contains a series of pairs of contact wires d, d' (indicated in Fig. 1 and shown clearly in Fig. 2) to be bridged by the respective contact elements e. These wires d, d' are included in parallel electric 110 circuits, called tone circuits, which also include the magnets f, the correlation of the parts being such that when any pair of wires d, d' is bridged by the corresponding circuit closing element e, the circuit to the corresponding magnet f will be closed and said magnet energized when the corresponding tone duct 12 is opened.

The chamber L' similarly contains a series 115 of pairs of contact wires c, c' which are in parallel electric tone circuits which also include the magnets h, and which wires, when bridged by the respective circuit closing elements g, cause the corresponding magnets h to be energized when the corresponding tone ducts 12 are opened.

It will be noted that when the channel O contains air at atmospheric pressure all the bridging contacts e will be in contact with their respective pairs of contact wires d, d', 120

but it should be understood that if none of the tone ducts are opened, all of the circuits will be interrupted at the contact elements g^2 . In other words, while the bridging circuit closing elements e normally cause bridging relation with their respective pairs of contact wires d, d' , the tone circuits are interrupted until the corresponding tone duct is opened. If, however, any of the tone ducts be opened, the corresponding pneumatics g^3 will be deflated, thus closing corresponding tone circuits, such as presently traced, for example, which energize the corresponding magnets 91 and also energize the corresponding magnets f .

The tone circuits to the respective tone magnets 91 are as follows:

From the positive pole of a suitable source of electric potential P , by wire X and branch x^{14} to contact wire g^1 and through the bridging contact g^2 , contact wire g^3 and wires x^{15}, x^{16} to a terminal g^8 and through the corresponding magnet 91 to a terminal g^9 and back to the source P by way of wire x^{17} and bus bar Y . This energizes the corresponding magnet 91, resulting in the admission of atmospheric air to duct 90 and consequently to chamber 87. The valve having the members 84 and 85 now rises, thereby cutting off communication of the duct 81 with the suction chamber 83 and opening communication of said duct with the atmosphere. Air at atmospheric pressure is now admitted to corresponding chambers 80 ^{a} and 79 ^{a} , thereby raising the levers 77 and 75. The several contact wires d are connected by wires x^{18}, x^{19} to the respective terminals g^6 and the several contact wires d' are connected by wires x^{20}, x^{21} to one side of respective magnets f , the other sides of which magnets are connected with the negative bus bar Y by wire x^{18} .

From the foregoing the operation will be understood to be as follows:

It will be remembered that when magnet 45 is not energized the duct 42 will be closed by the valve 43, and in consequence channel O will be in communication with the atmosphere through duct 24, chamber 28 and atmospheric port 30. As chamber M' is under suction, it follows that the lever 61 will be pressed outward, and its circuit closing element e will thereby be held in engagement with the contact wires d, d' . This is the normal condition with respect to the entire series of levers 61, it being further remembered that there is one such lever for each manual tone, and that all the levers are under the influence of a common membrane E , one side of which is exposed to the atmospheric air in the channel O .

Similarly, it will be remembered that when the magnet 45 a is not energized the duct 42 a will be closed to the atmosphere, 65 and duct 50, and consequently channel N ,

will be under suction from chamber 32 a . As chamber L' is always under suction, it follows that the springs 59 will be effective to hold the contact lever 58 away from contact wires c, c' . This is the normal condition as 70 to all the levers 58 of the pedal scale, it being further remembered that there is one such lever for each pedal tone and that each lever is under control of a common membrane G , one side of which is exposed to the 75 air in the channel N .

This relation of the parts which has arbitrarily been called the "normal" one because it is the one which most frequently exists in the operation of the mechanism, results (1) 80 in the sounding of the manual tones or effects when neither control duct is open, (2) in the introduction of pedal tones or effects when control duct 1 is open, and (3) in the exclusion of manual tones or effects and the 85 sounding of pedal tones or effects only when both control ducts 1 and 2 are opened; as it will be recalled that magnet 45 a is in a pedal circuit of such nature that when control duct 1 is opened magnet 45 a will be energized 90 thereby changing the tension of the air in channel N to atmospheric, and that magnet 45 is in a "manual control circuit" of such nature that when control duct 2 is opened magnet 45 will be energized, thus changing 95 the tension of the air in channel O to less than atmospheric.

The "pedal control circuit" may be traced diagrammatically upon Fig. 1 as follows:

From a suitable source of electrical potential, indicated at P , by bus bar X branch x^{10} , contact wire x^{12} , contact b^5 , contact wire x^3 , wire x^4 to the magnet 45 a and from said magnet to a negative bus bar Y , by way of wire x^5 .

The "manual control circuit" may be traced diagrammatically on Fig. 1 as follows:

From the source of electrical potential P , by bus bar X , branch x' , contact wire x^{11} , 110 contact a^5 , contact wire x^{12} , and wire x^{13} to the magnet 45, and through the magnet and back to the source by way of wire x^{14} and the negative bus bar Y .

The operation of energizing magnet 45 a to 115 adjust the contacts g into bridging engagement with contact wires c, c' to include pedal tones or effects with manual tones or effects, and similarly the operation of energizing magnet 45 to adjust the contacts e 120 away from contact wires d, d' to exclude the manual tones or effects, occurs immediately prior to the opening of the ducts 12 for the notes to be affected. Moreover, the energizing of the magnets 45 and 45 a ceases at the 125 moment the duct or ducts 12 for the tones to be affected, are opened. The energizing of these magnets accordingly are preparatory functions tending to result in the inflation of membrane G and the moving of all con-

tacts g into bridging engagement with wires c, c' when magnet 45^a is energized and the moving of all of said contacts out of engagement with said wires when the circuit to this magnet is broken; and, similarly, tending to result in the deflation of membrane E and thus moving of all contacts e out of engagement with contact wires d, d' when magnet 45 is energized and the moving of all of said contacts into engagement with said wires when the circuit to the latter magnet is broken.

This tendency, however, is to be resisted or rendered non-effective with relation to the contacts corresponding to tone ducts which are open when either control duct is open, and to this end the hereinbefore referred to locking levers 75 and 77 are employed and the levers 58 and 61 are mounted to be severally held by said levers, respectively. The operating means for these locking levers, as already stated, are controlled from the tone circuits so that the respective locking levers are maintained in holding relation with respect to corresponding contact levers from the moment the corresponding tone ducts are opened to the moment they are closed.

When tone circuits as previously stated include the magnets 91, the illustrated connections are such that when a pneumatic g^3 collapses by the opening of a corresponding tone duct 12, the circuit to the corresponding magnet 91 may be traced as follows—from the positive bus bar X by branch x^{14} contact wire g' , bridging contact g^2 , contact wire g^4 , wire x^{15} and wire x^{16} , to the terminal g^6 of the magnet corresponding to the tone duct opened, and thence through said magnet to the negative terminal g^8 of the magnet and back to the negative bus bar Y, by way of wire x^{17} . When this magnet is energized, its armature 91^a is attracted, thus admitting atmospheric air to the duct 90, and thence to chamber 87, whereupon the particular membrane 88 which is influenced by the tension of the air in said chamber is inflated thus moving the corresponding valve to open channel 81 and duct 81^a to the atmosphere and cut off its communication with suction chamber 83. Air at atmospheric pressure is now simultaneously admitted to chamber 80^a through branch duct 81^c and to chamber 79^a through branch duct 81^b. This results in the simultaneous inflation of corresponding membranes 80 and 79 of the manual and pedal scales, respectively, and causes the corresponding levers 77 and 75 to be moved into the paths of the respective corresponding contact carrying levers 61 and 58, thus holding the latter levers in the positions occupied by them when the corresponding tone duct 12 was opened and holding them in that position until the duct is closed.

For example, when the organ is first started, and assuming that the first tone or

tones are manual tones only, and hence all contacts e are in engagement with their respective pairs of contact wires d, d' , and all contacts g are out of contact with their respective pair of contact wires c, c' (neither control duct being open at this time) the opening of any tone duct 12 will complete the circuit through the corresponding magnet 91 whereupon the corresponding membranes 79 and 80 will immediately become inflated, the inflation of membrane 80 acting to move lever 77 into such position with relation to corresponding lever 61 that the contact e on the latter cannot move away from the contact wires d, d' , and the inflation of membrane 79 moving its lever in such relation to the corresponding lever 58 that the contact g on the latter cannot move into bridging contact with contact wires c, c' . This relation of the parts is maintained until the tone duct is again closed, even if control duct 1, or both control ducts 1 and 2, meanwhile are opened. Accordingly manual tones corresponding to tone ducts 12 which are open at the time control duct 1, or control ducts 1 and 2, are opened continue uninterrupted until the circuits to the corresponding magnets 91 are broken by the closing of said tone ducts. It will be apparent that the breaking of the circuits to any magnet 91 results in the changing of the tension of the air in the corresponding pair of chambers 80^a and 79^a to less than atmospheric, thus deflating the corresponding pair of membranes 79 and 80 and allowing the springs 79^c and 80^c to become effective to force the levers 75 and 77 out of the paths of the levers 58 and 61. The control ducts are opened in advance of the opening of the ducts 12 corresponding to tones which they are to affect and are closed shortly after said tone ducts are opened.

To introduce pedal tones with corresponding manual tones, duct 1 alone is opened, the manual mechanism being normally operative as already stated. The opening of the duct will result in the energizing of magnet 45^a and this in turn will cause the membrane G to be inflated thus moving all the contacts g (except those which are stopped or barred by levers 75 corresponding to open tone ducts) into contact with the wires c .

If pedal tones are to be played without corresponding manual tones, then duct 2 is opened along with duct 1. The opening of control duct 2 results in the energizing of magnet 45 and this in turn will cause the membrane E to collapse and permit the springs 62 to become effective to move all the contacts e , (except those which are stopped or barred by levers 77 corresponding to open tone ducts 12) out of contact with wires c, c' .

It will be noted that the loose engagement between the stems 51 and the several levers 130

58 and between the stems 51^a and the several levers 61, permit relative movement between the stems and levers, respectively, necessary to the foregoing operation and that the 5 springs 59 and 62 exert a resilient pressure against the respective levers which is always operative to move the contacts e, g, away from the contact wires except when overcome by the tension of the air in channels N, O, or when restrained by levers 75 or 77.

Having thus described the invention what I believe to be new and desire to secure by Letters Patent, is:—

15 1. A record controlled musical instrument of the kind set forth, having tone connections for a plurality of scales of tone-emitting elements and including a circuit, a series of contact carrying levers in the tone 20 connections for each scale, each series having an operating membrane common thereto and elements loosely connecting each lever with the membrane, a series of pneumatically operated holding levers for the contact 25 carrying levers, and record-controlled means for controlling the air tensions which control the operations of the membrane and pneumatically operable holding levers.

2. A record controlled musical instrument of the kind set forth, having tone connections for a plurality of scales of tone-emitting elements and including a circuit, a series of pneumatically operable contact-carrying members in the tone connections 30 for each scale, a series of holding levers for each series of contact-carrying members, pneumatically-operable members, connections between said members and levers for transmitting motion from the former to the 35 latter, said connections being loosely engaged with the levers, and record controlled means for controlling the air tensions which control the operations of the contact carrying members and holding levers.

3. A record controlled musical instrument of the kind set forth having tone connections for a plurality of scales of tone-emitting elements and including a circuit; a series of levers carrying circuit closing 40 means for the tone connections, a membrane for operating the levers and common to a plurality thereof, and pneumatic means for operating the membranes.

4. A record controlled musical instrument of the kind set forth having tone connections for a plurality of scales of tone-emitting elements and including a circuit; a series of circuit closing levers, an operating membrane for and common to a plurality of 45 the levers, means for controlling the operation of the membranes.

5. A record controlled musical instrument of the kind set forth having tone connections for a plurality of scales of tone-emitting elements and including a circuit; a

series of circuit closing levers, an operating membrane for and common to a plurality of the levers, means for controlling the operation of the membranes, and means in the tone connections for locking the levers, corresponding to the tone sounded, in operated or unoperated position.

6. A record controlled musical instrument of the kind set forth having tone connections for a plurality of scales of tone-emitting elements and including a circuit; a series of circuit closing levers, an operating membrane for and common to a plurality of the levers, means for controlling the operation of the membranes, and means in the tone connections for preventing the membrane from operating the lever, corresponding to that tone, as long as the tone is sounded.

7. A record controlled musical instrument of the kind set forth having tone connections for a plurality of scales of tone-emitting elements and including a circuit; a series of circuit closing levers, one for each tone of each scale, means whereby the levers are operated in one direction, means, including a membrane, whereby the levers are moved in another direction, record controlled means for controlling the tensions which control the operation of the membranes.

8. A record controlled musical instrument of the kind set forth having tone connections for a plurality of scales of tone-emitting elements and including a circuit; a series of circuit closing levers, one for each tone of each scale, means whereby the levers are operated in one direction, means, including a membrane, whereby the levers are moved in another direction, record controlled means for controlling the tensions which control the operation of the membranes, and means in the tone connections for maintaining in position the levers corresponding to the tone being played, as long as the tone is being played.

9. A record controlled musical instrument of the kind set forth having tone connections for a plurality of scales of tone-emitting elements and including a circuit; a series of circuit closing levers, one for each tone of each scale, means whereby the levers are operated in one direction, means, including a membrane, whereby the levers are moved in another direction, record controlled means for controlling the tensions which control the operation of the membranes, and locking means in the tone connections for maintaining in position the levers corresponding to the notes being sounded, as long as the respective notes continue to be sounded, said locking means comprising locking levers, means carried by the levers and engaging the circuit closing levers to lock the same against movement, membranes for operating the locking levers.

10. A record controlled musical instrument of the kind set forth having tone connections for a plurality of scales of tone-emitting elements and including a circuit; a series of circuit closing levers, one for each tone of each scale, means whereby the levers are operated in one direction, means including a membrane, whereby the levers are moved in another direction, record controlled means for controlling the tensions which control the operation of the membranes, locking means in the tone connections for maintaining in position the levers of each scale corresponding to the notes being sounded, as long as the respective notes continue to be sounded, said locking means comprising locking levers, one for each circuit closing lever, means carried by the levers and engaging the circuit closing levers respectively to lock the same against movement, a membrane for each locking lever for operating the same, and means whereby the locking levers of the different scales, corresponding to the same note, will be operated simultaneously.
11. A record controlled musical instrument of the kind set forth having tone connections for a plurality of scales of tone-emitting elements and including a circuit; a series of circuit closing levers for the tone connections of each scale, membranous means for operating the levers, loose connections between the membranous means and the levers to transmit motion from the former to the latter, and pneumatic means for controlling the pressure on said membranous means to operate the levers.
12. A record controlled musical instrument of the kind set forth having tone connections for a plurality of scales of tone-emitting elements and including a circuit; a series of circuit closing levers for the tone connections of each scale, membranous means for operating the levers, loose connections between the membranous means and the levers to transmit motion from the former to the latter, pneumatic means for controlling the pressure on said membranous means to operate the levers, pneumatically operated holding levers for the circuit closing levers, and a record controlling means for controlling the air tension which controls the operations of the membranous means and pneumatically operated holding levers.
13. A record controlled musical instrument of the kind set forth having tone connections for a plurality of scales of tone-emitting elements and including a circuit; a series of circuit closing levers for the tone connections of each scale, membranous means for operating the levers, connections between the membranous means and the levers, the connections being in position to be moved by the membranous means, the membranous means and the last mentioned connections being mounted so as to be capable of movement one relative to the other.
14. A record controlled musical instrument of the kind set forth having tone connections for a plurality of scales of tone-emitting elements and including a circuit; a series of circuit closing levers for the tone connections of each scale, membranous means for operating the levers, connections between the membranous means and the levers, the connections being in position to be moved by the membranous means, the membranous means and the last mentioned connections being mounted so as to be capable of movement one relative to the other, record controlled devices for controlling the pressure on the membranous means and other record controlled devices for controlling the levers independently of the said membranous means.
15. A record controlled musical instrument of the kind set forth having tone connections for a plurality of scales of tone-emitting elements and including a circuit; a series of circuit closing levers for the tone connections of each scale, membranous means for operating the levers, connections between the membranous means and the levers, the connections extending into the respective levers and loosely connected thereto.
16. A record controlled musical instrument of the kind set forth having tone connections for a plurality of scales of tone-emitting elements and including a circuit; a series of circuit closing levers for the tone connections of each scale, membranous means for operating the levers, connections between the membranous means and the levers, the connections extending into the respective levers and loosely connected thereto, and record controlled devices for controlling the pressure on the membranous means and other record controlled devices for controlling the levers independently of the said membranous means.
17. A record controlled musical instrument of the kind set forth, having tone connections for a plurality of scales of tone-emitting elements and including a circuit; a series of circuit closing levers for the tone connections of each scale, membranous means for operating the levers, an element having one end in position to be operated by the membranous means and the other end in position to operate the lever.
18. A record controlled musical instrument of the kind set forth, having tone connections for a plurality of scales of tone-emitting elements and including a circuit; a series of circuit closing levers for the tone connections of each scale, membranous means for operating the levers, an element having one end in position to be operated by the membranous means and the other end in position to operate the lever.

sition to operate the lever, and record controlled devices for controlling the pressure on the membranous means and other record controlled devices for exercising control over the levers independently of the said membranous means.

19. A record controlled musical instrument of the kind set forth, having tone connections for a plurality of scales of tone-emitting elements and including a circuit; a series of circuit closing levers for the tone connections of each scale, membranous means for operating the levers, a longitudinally movable element having one end in position to be operated by the membranous means and the other end in position to operate the lever.

20. A record controlled musical instrument of the kind set forth, having tone connections for a plurality of scales of tone-emitting elements and including a circuit; a series of circuit closing levers for the tone connections of each scale, membranous means for operating the levers, a longitudinally movable element having one end in position to be operated by the membranous means and the other end in position to operate the lever, and record controlled devices for controlling the pressure on the membranous means and other record controlled devices for exercising control over the levers independently of the said membranous means.

21. A record controlled musical instrument of the kind set forth having tone connections for a plurality of scales of tone-emitting elements and including a circuit; a series of circuit closing levers for the tone connections of each scale, pneumatic means for operating the levers, stems connecting the pneumatic means and the levers for operating the latter from the former, and means for controlling the pressure on the pneumatic means.

22. A record controlled musical instrument of the kind set forth having tone connections for a plurality of scales of tone-emitting elements and including a circuit; a series of circuit closing levers for the tone connections of each scale, pneumatic means for operating the levers, stems connecting the pneumatic means and the levers for operating the latter from the former, and record controlled devices for controlling the pressure on the pneumatic means and other record controlled devices for controlling the

movement of the levers independently of the pneumatic means.

23. A record controlled musical instrument of the kind set forth having tone connections for a plurality of scales of tone-emitting elements and including a circuit; a series of circuit closing levers for the tone connections of each scale, membranous means for operating the levers, said membranous means being within a tension chamber, means controlling the relative pressure inside and outside of said membranous means.

24. A record controlled musical instrument of the kind set forth having tone connections for a plurality of scales of tone-emitting elements and including a circuit; a series of circuit closing levers for the tone connections of each scale, membranous means for operating the levers, said membranous means being within a tension chamber, means controlling the relative pressure inside and outside of said membranous means, and record controlled devices for interrupting the movement of the levers.

25. A record controlled musical instrument of the kind set forth having tone connections for a plurality of scales of tone-emitting elements and including a circuit; a series of circuit closing devices for the tone connections of each scale, means for operating the devices, means including a membrane for controlling the movement of the devices independent of the operating means.

26. A record controlled musical instrument of the kind set forth having tone connections for a plurality of scales of tone-emitting elements and including a circuit; a series of circuit closing devices for the tone connections of each scale, means for operating the devices, record controlled means, including a membrane, for controlling the movement of the devices independent of the operating means.

27. A record controlled musical instrument of the kind described having tone connections for a plurality of scales of tone-emitting elements and including a circuit; a box having a tension chest, a series of circuit closing elements in the tone connections, membranous means for operating the circuit closing elements and being within the tension chest.

In testimony whereof I affix my signature.

HEINRICH BOCKISCH.
